SPARK PLUG

Frank A. Carter and Frank J. McAvoy,
Roselle Park, N. J.

Application May 31, 1935, Serial No. 24,407

5 Claims. (Cl. 123—169)

This invention relates to an improved spark plug, has primary reference to spark intensifying means for said plug, and in particular relates to an intensifier unit in the nature of an attachment susceptible of being applied to a conventional marketed type of plug such as is now commonly used.

By way of introduction and without attempting to attach emphasis or importance to the attachment idea of the invention, we would like to point out that the inventive conception comprehends the adoption and use of spark intensifying means which embodies a new basic principle of operation in that it serves to provide a spark gap at the time of initial starting of the motor when the motor and plug is cold and automatically throws said plug intensifying gap out of play as soon as the motor becomes heated to a predetermined degree.

Needless to say, we are aware that spark intensifying devices for spark plugs are not new. Generally stated it would appear that the prior art shows many different types of intensifiers most of which are of the permanent type although some adjustable features are incorporated therein. That is to say, the customary structure with which we are familiar includes a sectional electrode wherein a space is maintained permanently between the electrode sections to provide a spark gap be it adjustable or not.

We deem it logical to also say that temperature variable spark intensifying means in the spark plug construction is also not new. For example, in a patent to one W. P. Kerrigan 1,484,335 of February 19, 1924 there is provided a spark plug having in combination with its spark gap a supplemental spark intensifying gap and electrically conducting thermostatically operating means arranged to bridge the gap wherein said means is arranged to automatically break the temporary connection between the electrode end when the plug becomes heated.

By way of contrast with this prior patent which may be utilized as a convenient guide to introduction of the novelty which we claim, it is to be noted that we have evolved and produced a structure which involves an absolutely reverse principle and arrangement. Or stated otherwise, we have perfected a spark intensifier utilizing a supplementary electrode element, and a thermostatically controlled contacting element of a relatively movable type wherein said latter element is in the form of a normally expansible coiled spring with its contact end spaced away from

the adjacent element so long as the plug and engine is cold, but serves to automatically close the gap and keep it closed when the motor becomes heated, whereby to permit the plug to operate as though the intensifier were not present.

The particular manner in which this is accomplished will become more readily apparent from the following description and the accompanying illustrative pictorial drawing.

In the drawing wherein like numerals are employed to designate like parts throughout the same:

Figure 1 is a view partly in section and partly in elevation showing the conventional plug with the intensifier unit or attachment applied thereto.

Figure 2 is a top plan view with the terminal returning or clamping nut removed to disclose the details of the attachment.

Figure 3 is a sectional view illustrating the parts a little more in detail.

Referring now to the drawing by distinguishing numerals it will be observed that the conventional spark plug is denoted by the numeral 4 and this includes the usual insulating body 5, the retention fitting 6, the central electrode terminating in a contact 7 cooperable with the customary L-shaped spark gap contact 8. Ordinarily, the upper end of the electrode, that is the end which projects above the insulator 5 is screw threaded as indicated at 9 and we take advantage of this arrangement by connecting the attachment 10 thereto. In other words, we substitute the attachment for the usual clamping nut but also use a similar clamping nut 11 to hold the terminal or current conductor wire (not shown) in place. The attachment or unit comprises a suitable insulating base or device 12 having a screw-threaded bushing 13 fitted into the socket portion thereof said bushing being connectible with the screw threaded end 9 of the electrode. The laterally directed end 14 of the supplementary external contact element 15 is imbedded in the insulation 12 and electrically connected with the bushing 13 and therefore electrically joined to the electrode 9. The wire connecting element comprises a disk-like head 16 secured by suitable fasteners 17 to the insulator 12 and this is provided with a screw threaded shank or stud 18 to accommodate the wire or terminal clamping nut 11. The current conductor means to carry the current from the stud 18 to the electrode 9 comprises the afore-said L-shaped contact 15 and the complementary

coiled spring 19. This coiled spring is anchored at one end as indicated at 20 in Figure 2 in the insulator 12. This laterally anchored end, however, has electrical connection with the disk 16. 5 The free end of the outer convolution of the coil, that is the convolution 21 terminates in a laterally directed element 22 which may be conveniently described as a movable contact and this is cooperable with the stationary contact 15. 10 So long as the plug is cold, this thermostatic coil spring expands under its natural inherent resiliency and provides a spark gap as shown in Figure 4. When the motor reaches a predetermined point of heat the metal expands and 15 closes the gap thereby the current flows steadily through the electrode as though the intensifier attachment were not present.

With our attachment it is obvious that the gap closes with a few degrees rise in temperature and 20 remains closed so long as the motor is in motion, thereby making it possible to adjust spark plug points to the best running gap. In most motors the best results are obtained when the gap in the plug is .028. But when the motor is cold it is 25 difficult to start and in some of the high compression type motors it is extremely difficult to start. Our invention completely overcomes the likelihood of the motor not starting when it is cold, for it provides the desired spark intensifying 30 gap at this particular period in starting. When, however the motor becomes heated and this amplified spark is unnecessary, the intensifier automatically "goes off" so to speak since it is not needed during the normal running of the motor. 35 That it is possible to adjust the device in such a manner that one can obtain any of the results now claimed on most all intensified plugs. For instance, if a permanent gap is desired move part 15 far enough away from 22 to cause spark to 40 jump to next coil on 21, which in any case is never more than .030. If no intensification is desired, press 15 to and against 22. If no intensification spark is desired in starting cold motor and is desired after motor is warm, move 15 to opposite side of 22. 45

It is thought that persons skilled in the art to which the invention relates will be able to obtain a clear understanding of the invention after considering the description in connection with the 50 drawing. Therefore, a more lengthy description is regarded as unnecessary.

Minor changes in shape, size and rearrangement of details coming within the field of invention claimed may be resorted to in actual practice, if desired. 55

Having thus described the invention, what is claimed as new is:

1. A spark plug comprising an insulator having an electrode extending therethrough, a fitting connected with said insulator, complementary spark points cooperable with the fitting and electrode in the customary manner, and spark in-

tensifying means associated with said electrode, said intensifying means being of a thermostatically controlled type and being normally open to provide an additional spark gap when the plug and motor is cold, and closed and retained closed 5 as soon as the temperature of the plug rises to a predetermined degree.

2. As a new article of manufacture, an intensifier attachment connectible with the screw threaded end of the electrode in a conventional 10 spark plug comprising an insulator provided with a current conducting element of a stationary type connectible with said electrode, terminal connector means, and a thermostatically controlled current conductor element electrically 15 connected with said terminal connector means and associated with said current conducting element in the insulator and normally spaced therefrom to provide an intensifying gap when the metal is cold, and automatically movable into 20 closing engagement with said contact when the metal is heated.

3. A spark plug including customary point and electrode and assembling means therefor, and an accessible externally arranged spark intensifying device cooperable with the electrode and including terminal connector means and electrically conducting thermostatically operated 25 means.

4. A spark plug including customary point and electrode and assembling means therefor, and an accessible externally arranged spark intensifying device cooperable with the electrode and including terminal connector means and electrical 30 conducting thermostatically operated means, 35 said last named means embodying a stationary rigid contact member and a complementary coiled spring, the inherent resiliency of said spring serving to normally separate the end of the spring from the contact element to provide a limited 40 spark gap, said spring being acted on by a predetermined degree of heat to automatically close the spark gap and to keep it closed during the running of the motor.

5. A spark intensifying attachment of the class 45 described comprising an insulator provided with a socket having a metallic bushing fitted therein and screw threaded to fit on the customary electrode, terminal wire attaching means mounted on said insulator, a thermostatically controlled 50 electricity conducting coiled spring carried by the insulator, electrically connected with said terminal connector means and having a laterally directed free end portion, a substantially L-shaped current conducting element rigidly imbedded in 55 said insulator and having its inner end connected with said bushing and having its outer end exposed and cooperable with the free end of said spring.
